CATHODE BEAM TUBE

Paul K. Weimer, Princeton, N. J., assignor to
 Radio Corporation of America, a corporation
 of Delaware

Application November 28, 1945, Serial No. 631,440

2 Claims. (Cl. 250—156)

1

This invention relates to television pick-up tubes in which the electrons of the beam are decelerated substantially to zero electron velocity at the target, upon which part of the beam electrons land in proportion to the image charge and the remainder return towards the gun and land on a multiplier dynode. The invention is particularly suitable for television pick-up tubes having two-sided targets, one side of which is scanned by the beam and the other side bombarded by photo-electrons from a photocathode to produce the charge image. This type of tube is disclosed in my application filed September 16, 1944, Serial No. 554,494, now U. S. Patent 2,433,941, issued January 6, 1948. The pick-up tube disclosed in that application is called an "image orthicon" and that name will be applied to the tube in this disclosure.

The image orthicon has customarily been operated with a wall coating supplied with about 100 volts and with an electromagnetic focusing field of about 80 or more gauss, which causes the tube to operate with six or more orders of focus between the first stage of the multiplier and the target. To obtain improved resolution it is desirable to operate the pick-up tube with a higher wall coating voltage, which would give a lower order of focus. Also, in this same image orthicon, it is desirable to use fewer ampere turns for the electromagnetic deflection coils, so as to reduce the power cost in operating the tube. This can be done if the electromagnetic focusing field is reduced in strength, which likewise gives a lower order of focus. When these two changes were made in the past, it was found the lower order of focus caused non-uniform landing of the beam electrons over the target area, with complete failure of the beam to land at the edges of the picture area, or raster.

It is an object of this invention to construct a tube so that there will be uniform landing of electrons over the whole target area.

Another object of the invention is to construct a television pick-up tube in which the beam electrons land on the outer portion of the target with the same velocity as on the inner portions.

Other objects will appear in the following description, reference being had to the drawings, in which:

Fig. 1 is a diagram illustrating the magnetic field of the deflection coil alone of a cathode ray tube.

Fig. 2 is a diagram illustrating the resultant of the deflection field and the focusing field in a cathode ray tube.

2

Fig. 3 is a diagram illustrating the phase relations at the target of the helical motion of the electrons in a cathode ray tube.

Fig. 4 is an illustration of a television pick-up tube embodying the invention.

Fig. 5 is an end view of the tube of Fig. 1.

Fig. 6 is a modification showing a different form of decelerating lens.

The effect of non-uniform landing of the beam 10 on the target is to produce a dark shading signal obscuring certain sections of the picture. This shading, which tends to occur most prominently near the edges of the picture and diminishes substantially to zero at the center, is due to the failure of the beam to approach sufficiently close to the target to deposit any electrons. The non-uniform landing of the beam on the target is associated with the helical motion of the beam.

In its travel toward the target, the electron 20 usually acquires a small transverse velocity v_t perpendicular to the magnetic focusing field. Its path down the tube is then a helix whose radius is given by the equation

25

$$R = \frac{3.36\sqrt{Vt}}{H} \text{ cm.}$$

where Vt is the transverse velocity component v_t expressed in volts and H is the magnetic field in gausses.

The total kinetic energy of the electron at any point is determined by the space potential at that point. Any helical energy must, therefore, be acquired at the expense of the longitudinal energy. If the helical energy is retained as the electron approaches the target, the electron will fail to strike the target by the voltage equivalent of the energy of helical motion. The result is the partial or complete loss of signal in the regions where the beam fails to discharge the target. For a uniformly shaded picture with tubes of the image orthicon type, the beam must land uniformly over the entire target to within a tenth of a volt. At the same time, the helical motion producing non-uniform landing may amount to as much as 5 or 10 volts.

The helical motion contributing to non-uniform landing is of two types: (A) that motion introduced independently of deflection, and (B) that introduced by or as a result of deflection. In type A the chief source of helical motion is mechanical misalignment of the gun or multiplier with respect to the tube or to the magnetic field. Other sources may be extraneous electric or magnetic fields whose effects are not sym-

metric about the axis of the tube. In type B two equally important sources of helical motion are the deflection coil and the decelerating lens. In either case the effect is a maximum at the edges of the picture and negligible in the center.

The transverse motion arises in the deflection coil due to the curvature in the magnetic field at the ends of the coils, as shown in Fig. 2. In general, the helical motion is greater for higher voltage on the wall, lower magnetic fields, shorter deflection coils, and greater angles of scan. As shown in Fig. 2, the fringe field of the deflection coil combines with the focusing field to give a resultant field in which the curvature of the bend at the exit end of the coil is greater than at the entrance end, as shown at *a*, *b* and *c*, *d* respectively, for an electron entering along the axis of the tube, although the total angle of each bend is the same. The result of this fact is that although both bends contribute to the total helical motion produced by the deflection coil, the second bend produces the greater effect and so has more influence in controlling the phase of the resultant helical motion.

The helical motion produced by the deceleration lens at the edge of the picture is due to the components of the electric field perpendicular to the magnetic field. This transverse component produces on the electron a force which is radial outward throughout most of the deceleration path and which rises from zero to a maximum and falls to zero again within the deceleration region. The phase and magnitude of the helical motion generated by the deceleration lens are dependent on the wall coating voltage, electrode configuration near the target, the magnetic field and the diameter of the lens ring, that is, its distance from the axis of the tube.

The helical motions of types A and B discussed above have different phase relations over the target. If the beam possesses helical motion before deflection (type A), the phase after deflection will appear as indicated by the arrows at A in Fig. 3, assuming that the deflection introduces no additional helical motion. The type B motion, illustrated at B in Fig. 3, is such that the electron at all parts of the picture moves in the same direction (same angle) relative to a line connecting the axis of the tube to that point. At the right of Fig. 3 the resultant of the two effects A and B is shown with elimination of helical motion occurring in the lower right-hand corner, the arrows indicating the direction of the helical motion in the other parts of the picture. The recognition of the difference of these two types of helical motion is necessary in order to obtain good landing at the target.

Uniform landing of the beam on the target requires that the helical motion of the beam of both types be negligible as the electron approaches the target. This, however, does not require that the motion be small throughout the entire path of the electron from gun to target. The fundamental principle for eliminating helical motion at the target thus consists of balancing the sources of helical motion in phase and magnitude so that the resultant effect at the target is substantially zero. A necessary requirement, however, is that the sources to be balanced be of the same type; that is, in type B the effect of the deflection coil may be balanced by effect of the deceleration lens and in type A the effect may be balanced by means of a special alignment coil.

In tubes of the image orthicon type, the gun is axially centered in the tube, with a multiplier

which introduces no transverse electric field on the axis. An alignment coil is necessary only for those tubes in which a mechanical misalignment of the gun or persuader electrode has occurred, or for tubes which are not correctly aligned in the focusing field. It has been found possible to make an electrical correction for these misalignments by introducing over the envelope near the gun a weak magnetic field perpendicular to the axial field and extending about an inch in length, as disclosed in the application of Albert Rose, filed April 11, 1942, Serial No. 438,562, now U. S. Patent 2,407,905, issued September 17, 1946. This results in a bend or kink in the field lines just in front of the gun, which would of itself introduce helical motion of type A. By rotational adjustment of the alignment coil and by variation of current within the coil, an operating condition may be found in which the coil will cancel the initial misalignment.

In practice, the adjustment of the alignment coil is made while observing the picture to ascertain when the most uniform landing in the center of the picture is obtained. When the correct compensation has been made with the alignment coil, the remaining non-uniformity of landing will appear as a dark shading at the edges. This is due to helical motion of type B introduced by the deflection coil or the deceleration lens, or both. The dark edges of the picture due to type B helical motion are not objectionable when the wall coating voltage is low and the magnetic field high, giving many orders of focus between the gun and the target. Such a mode of operation as above indicated, however, is not desirable from the standpoint of resolution and power required for deflection. Under normal operating conditions with five focal loops between gun and target (e. g., with a wall voltage of 127 volts and magnetic field of 56 gauss), the helical motion introduced by either the deflection coil or the deceleration lens is of the order of 5 volts at the edge of the target. If uniform landing to within 0.1 volt is to be achieved at the target, it is apparent that means are required to cancel this motion before the beam reaches the target.

It has been found possible to obtain uniform landing over the entire picture by balancing the effect of the deceleration lens against the deflection coil in such a way that the lens transforms the helical motion introduced by the deflection back into the longitudinal energy necessary for landing. The magnitude of helical motion required for cancellation is obtained by the design of the tube and deflection coil for a specified wall voltage and magnetic field intensity. The correct phase for cancellation is obtained by adjusting manually for best landing the distance of the deflection coil from the deceleration lens. This adjustment may be easily made without disturbing the focus of the picture and, even though the magnitudes of the two sources may be slightly mismatched, there is always a "best position" of the deflection coil. There may, however, be more than one position of the deflection coil which will give the proper phase at the deceleration lens for cancellation. These occur at a distance apart equal to λ , the distance between the nodes in the beam. This is given by

$$\lambda \text{ (cm.)} = \frac{21.2\sqrt{V}}{H}$$

where V is the wall voltage in volts and H the magnetic field in gauss.

It has been found that the balance between

the deceleration lens and the deflection coil is unchanged if the wall coating voltage and magnetic field are varied together so that

$$\frac{\sqrt{V}}{H}$$

remains constant. In general, the balance of these two sources of helical motion is a function of the following factors:

(1) Structural dimensions of the tube between gun and target, with the decelerating ring structure being most critical;

(2) Length, diameter and winding arrangement of the deflection coil;

(3) Uniformity and intensity of the axial magnetic field, especially over the target;

(4) Voltage on the wall coating, decelerating ring and persuader;

(5) Position of deflection coil relative to the target.

The last three factors may be varied while observing the picture, but the positioning of the deflection coil relative to the target offers the most satisfactory final adjustment for attainment of good landing. This is due to the fact that this adjustment does not change the focus of the picture, or affect the size of the return pattern to any great extent.

The manner in which the phase balancing is best obtained in cathode ray tubes of the type disclosed in my said application will appear from the description of the drawing.

Referring to Fig. 4, the evacuated envelope 1 contains a gun 2 at one end thereof with a target 3 and photocathode 4 at the other end.

The gun 2 consists of the usual indirectly heated cathode 5 (the heater not being shown) surrounded by the control electrode or grid 6. Around the grid is the anode 7, the end 8 of which constitutes the first dynode of the multiplier. In the drawing, the cathode, grid and first anode are partially sectioned to illustrate their spaced relation and tubular construction. The grid and first anode have the usual minute orifices, as indicated, through which the beam 9 is projected to reach the target with approximately zero velocity. Tubular electrode 10 is axially placed around the front part of the gun adjacent thereto. This is usually referred to as a "persuader," because its function is to direct the secondary electrons emitted by the first dynode 8 into the succeeding multiplier dynode, as will be hereinafter referred to. Wall coating 11 is applied to the inner wall of envelope 1 in known manner.

Outside the envelope 1 is placed the deflecting coil unit 12, consisting of a frame 13 having two electro-magnetic coils with their field axes perpendicular to each other and to the longitudinal axis of the tube. One of these coils deflects the beam in a vertical direction in Fig. 1 and the other deflects it at right angles to the plane of the drawing. These coils are of well known construction and hence have not been individually shown. It will be understood that the deflection coils will have periodically varying voltages applied thereto, say by saw-tooth generators (not shown) of suitable frequencies, to produce line and frame scansion.

Outside of the envelope 1 is the compensating coil 14 having a field perpendicular to the axis of the tube, as disclosed in said application of Albert Rose. As shown in Figure 4 coil 14 comprises two separate coils connected in series and

indicated by the cross-hatched and dotted lines. These two coils are similar to those used in the deflecting unit 12 and are of well known construction. The current passing through the two coils

5 at 14 will provide a magnetic field essentially in a plane perpendicular to the axis of the tube 1. By adjusting this coil circumferentially around the tube axis, helical motion of type B can be eliminated. Also, outside the coils 12 and 14 is 10 placed coil 15, which produces a strong magnetic focusing field parallel to the axis of the tube on both sides of the target.

Around the gun is placed a plurality of additional multiplier dynodes 16, 17, 18 and 19 and 15 a collecting electrode 20, which is a screen of suitable mesh. This collector electrode is connected to the desired utilization, such as an amplifier tube (not shown). The multiplier dynodes are particularly described in my said application and it will be sufficient to say respecting the dynodes 16, 17 and 18 that each consists of a disc of metal having angularity displaced radial blades 22, somewhat like an electrical fan, held in a suitable annular frame and having a sufficient axial opening to pass in non-conducting relation over the first anode 7.

In front of the blades of the dynodes shown are screens 23 secured to the frames so as to be in electrical contact with the associated multiplier blades 22, from which they are suitably spaced. The multiplier dynodes 16, 17 and 18 are partially broken away to show the blades and screens.

The multiplier dynode 19 is the final multiplier stage and consists of a flat annulus spaced from 35 and surrounding the first anode, similarly to the other dynodes. The multiplier dynodes 8, 16, 17, 18 and 19 may be made of any metal having good electron-emitting properties, or may have a coating of active material to produce suitable emission of secondary electrons upon bombardment by primary electrons. The gun cathode 5 is connected to ground. By way of example, the voltages of the various electrodes are indicated on the drawing, the voltages being in relation to ground.

At the front end of the tube, the photocathode 4 may be a semi-transparent coating of light-sensitive emissive material on the inside of the end of the envelope 1. A metal frame 24 supports the thin glass target 3, such as disclosed in the application of Albert Rose, filed September 20, 1940, Serial No. 357,543, abandoned in favor of continuation application Serial No. 631,441 filed November 28, 1945, which now is U. S. 55 Patent 2,506,741 issued May 9, 1950, collecting screen 25 spaced from the target, as disclosed in the application of Harold B. Law, filed April 19, 1945, Serial No. 589,241 now U. S. Patent 2,460,093, but it may be spaced and supported in any other 60 desired way. The various electrodes would be supported in the tube envelope in well-known ways, not illustrated.

Adjacent the target 3 is arranged the decelerating ring 26, which is grounded to gun cathode potential or thereabouts. Between the frame 24 and the photocathode 4 is electrode 27, which is connected to a potential more negative than ground, as disclosed in my said application. The photoelectrons bombarded by the light image 70 from photocathode 4 are accelerated at high electron velocity to the target 3 along the magnetic lines of the focusing coil 15 and bombard secondaries therefrom, which are collected by screen 25. This sets up a charge image on the target 3.

The parts thus far described are disclosed in

my said application and are not, per se, claimed herein.

The means by which the helical motion of type B is balanced out is shown in Figs. 4 and 5. This consists of a rack 28 attached to the frame 13 of the deflection coil. Pinion 29 on shaft 30 meshes with this rack. Knurled head 31 on shaft 30 permits manual adjustment of the deflection coil 12 toward and from the decelerating lens 26 for balancing out the helical motion of type B. These parts are mounted on a cylinder 32 fitting over the envelope 1. A flange 33 having an opening for passage of rack 28 is welded to, or is otherwise fastened to, the end of this cylinder. The compensating coil 14 is rotatably mounted on a second cylinder 34 welded or otherwise fastened to flange 33 outside rack 28. The cylinder 32 is cut at 35 partially around its periphery at the gun end and bent into ears 35', through which bolt 36 is passed, so that the cylinder 32 may be rigidly clamped into position on the envelope 1. Fiber gaskets or the like (not shown) may be placed under the clamping ring to prevent breakage of the envelope. Ears 36a, 37 welded to the cylinder 32, together with the opening in flange 33, act as a guide for the movable rack 28. Shaft 30 is journaled in these ears, which also hold the pinion 29 in position on the rack. A bracket 38 may have one end welded to cylinder 32 and the other end secured, as by screws 39, to the frame of the focusing coil 15.

In the operation of the tube, the light image of the object to be transmitted is focused on the photocathode 4 and this ejects electrons from the photocathode. The electrons are accelerated under action of relatively positive electrode 27 and screen 25 along the lines of the electro-magnetic focusing field and strike glass target 3. Secondary electrons are bombarded therefrom and are collected by screen 25. Thus, a charge image is set up on the side of the target remote from the gun 2 representative of the light image. This sets up a potential pattern at the other side of the target and electrons from beam 9 land thereon in sufficient number to discharge the charges on the other side adjacent screen 25. This discharge is accomplished by passage through the glass target which is sufficiently conductive for transverse currents, but of sufficient resistance to prevent passage of the electrons or spreading of the potentials transversely over the target, as explained in said Rose and Law applications. The beam 9, modulated by loss of the electrons, returns toward the gun 2 and lands on the first dynode 8. The secondary electrons bombarded therefrom pass through the screen 23 under influence of the potential thereof, as well as the potential of persuader electrode 10, and bombard from the vanes 22 secondary electrons in multiplied number, which are attracted into the third multiplier stage. This is repeated in the remaining stages until secondary electrons from the dynode 19 of the final stage in greatly increased number are collected by screen electrode 20 and passed to the amplifiers (not shown) and thence to a local kinescope in which the picture can be observed. The amplified signals, of course, are then transmitted to a distance for reception as desired.

As already indicated, the coil 14 will be manually rotated until the best picture at the middle of the target is obtained in the local kinescope. This eliminates the type A helical motion. Then, knurled head 31 is turned back and forth until the picture becomes clear all the way to the outer edges by adjustment of the deflection coil

12 toward or from the decelerating lens 26. This eliminates or greatly reduces the type B helical motion.

It will be apparent that the deflection coil may be moved by various mechanisms without departing from the scope of the invention.

In the modification shown in Fig. 6, a decelerating electrode 48 of screen form operated at or slightly above the wall coating voltage is shown in place of the decelerating ring 26. This modification is fully disclosed in U. S. Patent 2,462,619, issued November 20, 1948, to P. K. Weimer. The lens effect of the decelerating member is greatly reduced by the uniform field produced thereby in front of the target. This greatly reduces the helical motion due to the decelerating electrode and there is usually insufficient helical motion introduced in this modification to balance out that of the deflecting coil with the same coil design. The deflecting coil can then be constructed to balance the effect of the bend at the emerging end of the coil against that of the bend at the entering end, as previously referred to herein. The small residual helical motion introduced by the deflection coil can be balanced against that of the screen 49, as described in connection with Fig. 4. The screen should be far enough from the target to be out of focus. Its best out-of-focus position is when 30 its distance from the target in centimeters equals

$5.3\sqrt{\text{Screen voltage}}$
Magnetic focusing field in gausses

35 In this type of decelerating electrode a spurious signal may be produced by interference between the outgoing beam and the return beam, depending upon the transit time of the electrons between their first and second passage through the screen. Any spurious signal may be reduced to negligible value by experimental adjustment of the distance between screen 40 and target 3 for best performance. Use of extra fine mesh screen of from 500 to 1000 mesh per inch makes the spurious signals of much less significance.

40 The use of a decelerating screen, as in Fig. 6, has the important advantage that the size of the scan of the return beam over the first dynode 8 is much reduced. This is due to the small lens effect of the screen as compared with that of a decelerating ring.

Having described my invention, what I claim is:

45 1. A cathode ray beam tube of the orthicon type comprising, an envelope containing a target, a gun having a cathode, grid and anode for projecting a beam of electrons toward said target, a wall coating anode and a decelerating electrode adjacent said target, means for producing an axial magnetic focusing field between the first mentioned anode and the target, a deflecting unit for producing two magnetic fields at right angles to each other and to said focusing field, and an adjusting device connected to said unit for moving it axially of the envelope towards and from said decelerating electrode to balance the helical motion produced by said unit.

50 2. An electron discharge device comprising, electron gun means for forming and projecting an electron beam along a path, a target electrode positioned transversely to said beam path and spaced therefrom, a decelerating electrode adjacent said target electrode and between said electron gun means and said target, means for producing an axial magnetic focusing field be-

tween said electron gun means and said target electrode, a deflecting unit for producing between said gun means and said decelerating electrode magnetic beam deflecting fields at right angles to said focusing field, and an adjusting device connected to said unit for moving said unit axially of said beam path toward and from said decelerating electrode to balance helical motion produced by interaction of said deflecting and focusing fields.

PAUL K. WEIMER.
